(57) **CLAIM**

The ornamental design for an LED ring light with tripod stand, as shown and described.

DESCRIPTION

FIG. 1 is a front perspective view of an LED ring light with tripod stand showing my new design where the LED ring light with tripod stand is in a first configuration of use shown with an unclaimed phone;

FIG. 2 is a front perspective view of the LED ring light with tripod stand where the LED ring light with tripod stand is in a second configuration of use shown with an unclaimed phone;

FIG. 3 is a front perspective view of the LED ring light with tripod stand of FIG. 2 shown without an unclaimed phone;

FIG. 4 is rear perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof; and,

FIG. 11 is an enlarged view of portion 11 shown in FIG. 4. The broken lines in the drawings depict environmental subject matter, specifically a phone in FIGS. 1 and 2, and portions of the LED ring light with tripod stand in all figures that form no part of the claimed design.
